UNITED STATES PATENT OFFICE.

JAMES SHORTT, OF LOS ANGELES, CALIFORNIA, ASSIGNOR TO ALLOY METAL PRODUCTS CO., OF LOS ANGELES, CALIFORNIA, A COPARTNERSHIP CONSISTING OF JAMES SHORTT AND CLAUDE E. CHAPMAN.

DESIGN FOR A HANGING ELECTRIC-LIGHT FIXTURE.

Application filed May 25, 1927. Serial No. 22,163. Term of patent 3½ years.

To all whom it may concern:

Be it known that I, JAMES SHORTT, a citizen of the United States, residing at Los Angeles, in the county of Los Angeles and State of California, have invented a new, original, and ornamental Design for Hanging Electric-Light Fixtures, of which the following is a specification, reference being had to the accompanying drawing, forming part thereof.

Fig. 1 is a side view of a hanging electric light fixture, showing my new design.

Fig. 2 is a diagrammatic plan view of Fig. 1 with the ceiling plate and supporting chain omitted.

I claim:

The ornamental design for a hanging electric light fixture, as shown.

JAMES SHORTT.
